UNITED STATES PATENT OFFICE.

LEWIS PEROTTI, OF NEWARK, NEW JERSEY.

PRESS.

1,415,611.

Specification of Letters Patent.

Patented May 9, 1922.

Application filed January 11, 1921. Serial No. 436,439.

To all whom it may concern:

Be it known that I, LEWIS PEROTTI, a citizen of the United States, and a resident of Newark, county of Essex, and State of New Jersey, have invented certain new and useful Improvements in Presses, of which the following is a specification.

This invention relates to a press, and is that type of press that is used for extracting 10 juices from fruits or vegetables, and is constructed so that it is easily operated.

The invention relates to a press of this type in which the basket that holds the material can be easily swung to and from its 15 position in which it is subjected to the pressure means of the press, so that it is not necessary to bodily lift the basket either to fill it or to empty it.

The invention is also designed to provide 20 a press of this kind which is compact, requiring but a minimum of head room, and which can be easily taken apart for the purpose of cleaning it.

The invention is illustrated in the accompanying drawings, in which Figure 1 is a side view of one form of my improved press, and Figure 2 is a central vertical section thereof. Figure 3 is a top view of the press shown in Figure 1, and Figure 4 is a section 25 showing the base of the support for the press in elevation, part thereof being broken away to show the interior construction. Figure 5 is a sectional detail of a ratchet mechanism for actuating the screw of the press. Figure 30 6 is a perspective view of one of the handles of the ratchet shown in Figure 5. Figure 7 is a detail section showing part of the base and part of one of the baskets and indicating the path that the juices which have been 35 extracted take in passing from the press. Figure 8 is a detail section on line 8—8 in Figure 4, and Figure 9 is a detail view showing one manner of attaching the basket support so that the proper location of the basket in relation to the pressure means is 40 assured.

The invention comprises a main support which is preferably cast and consists of a base portion 10 having a top part which includes a standard 11 which can be duplicated, as at 12, to form a support for the head 13 in which the pressure means is mounted, the pressure means in the form shown 45 consisting of a screw 14 working in the nut or screw-threaded bearing 16 in the top of the head 13 and being swivelled to the pis-

ton 17 and being operable by the ratchet device 18 which is provided with a removable handle 19.

The ratchet mechanism has a body portion 20 in which the handle 19 is seated, as shown in Figure 5, this body portion 20 being made short enough so that it can pass between the standards 11 and 12 and be completely rotated in the initial operation of the screw 14 so as to save time, but when leverage is required at the final stages of the pressing, the handle 19 is inserted, and for the purpose of its reciprocation I provide a ratchet mechanism which is shown in detail 70 in Figure 5 and consists of a pivoted pawl 21 which has teeth on its two ends, these teeth alternately engaging the teeth 22 of the ratchet 23.

On each side of the pawl 21 and in rear 75 of its two ends are the fingers 24, each of which is actuated by a spring 25 and each of which has a handle portion 26 projecting therefrom, and the operation of rotation of the ratchet can be controlled according to 80 which of the fingers 24 is retracted and made inoperative, permitting the other to have a spring action. Such retraction is possible by pushing back whichever of the fingers 24 is to be inoperative and catching the handle 85 26 in a lateral projection 27 of the slot 28, one of these slots 28 being provided on each side of the body portion. This, it will be evident, permits the ratchet to be reversed.

On one of the standards, preferably the 90 standard 11, is arranged a bracket 29 which is rotatably arranged on the standard and is provided with means for holding a basket 30. This basket 30 is open-ended, that is, the top and the bottom are open, and the 95 sides are made so that the juices can escape. The usual form is by making the body portion of the basket of wooden slats 31 which are separated slightly and which are surrounded by bands 32, and between the bands 100 and the slats is arranged the screening 33. The bracket 29 has projecting ears 34 and the bands 32 each have a lip 35, which lips are inserted in recesses in the ears, and then the pins 36 are passed down through a perforation in these elements so as to hold the 105 baskets in place, so that when the bracket 29 is rotated the basket is carried with it.

The bracket is usually provided with two opposed means, as above described, for holding the duplicate baskets, so that when one is in a position which places it in line with

the pressure means, the other is in position for filling. To permit such filling a temporary bottom is provided in the form of a plate 37 which swings by means of its hub 38 and which can be swung under the basket that is to be filled, indicated at *a* in Figure 3, and the contents are thus held up, and while the material in the basket under the pressure means is being compressed, the exposed basket is thus filled. When the basket at *a* is to be swung into position, the bottom 37, which is in the form of a plate, swings with it until it engages the edge 39 of the shallow part 40 of the shelf 41, the shelf 41 being approximately arcuate, and the material is thus suspended while this newly filled basket is being swung toward its position under the pressure means. Of course the false bottom 37 stops when it engages the shoulder 39 and forms a substantially flat surface in conjunction with the top surface of the shelf 41, since the top of the shelf and the top of the plate 37 are even, as will be seen from Figure 1.

When the baskets and their bracket have been swung on the standard 11 until the basket with the material that has been compressed is in the position shown at *b* in Figure 4, the caked or compressed material that is in the basket at *b* can be dropped, since there is nothing underneath the basket, and the bottom thus being open, pressure by any suitable instrument, such as a stick, serves to dislodge the material and it drops through. The travel of the baskets is then resumed and the newly filled basket is under the pressure means and the recently emptied basket is ready to be filled as soon as the false bottom 37 is again swung out to the position underneath this exposed or idle basket.

To insure the alignment of a basket under the pressure means I prefer to automatically halt the basket in such position, one such means being shown in detail in Figure 9, in which the latch pin 42, with the handle 43 for its manipulation, is normally projected by a spring 44 so that its end enters either of the recesses 45 in the standard 11, these parts being so disposed that when the latch 50 is in a recess one of the baskets is in position under the pressure means.

The base is provided with a recessed or depressed part 46 which forms a chamber 47 which has a lid 48 on the top, this lid preferably having a central opening 49 so that the juices may pass down through, the base having an annular groove 50 just outside of the basket so that juices squeezed through the screen 53 pass into this groove and through any desired number of passages 51 to the upper part of the chamber 47, as will be seen from Figure 7, the chamber 47 having an outlet tube 52 at the bottom. A screen 53 is installed so that it is beneath the passages 51 and is usually mounted on a frame

54 which has legs 55 which hold it above the bottom of the chamber 47.

The plate 37 which forms a temporary bottom for the basket that is being filled is also provided with an annular groove 56 which has an opening 57, so that any drippings from the material being placed in the basket or which rests for a time in the basket, run into the groove 56, the lowest point of which is provided with the opening 57 which is arranged near a curved groove or passage 58 which leads to one of the openings 51, as will be seen from Figure 4, whereby this material is also deposited on the screen 53 in the chamber 47 and passes out with the material from the other basket through the outlet 52 into a suitable receptacle on the outside of the press.

It will be seen that one or more baskets can be used in this press, and when a basket which has been filled in the exposed position at *a* in Figure 3 is desired to be swung around to its position under the pressure means, it necessitates only sufficient raising of the piston 17 of the pressure means to permit the basket to be passed under it. This eliminates any excessive raising of the pressure means and permits a compact press, since the head 13 is comparatively low.

The operation of the press is rapid, since there is no unusual delay in filling or emptying the baskets, since, as above described, material can be dropped from the basket when it is swung from under the pressure means to the position shown at *b* in Figure 4, and after it is emptied it can be at once placed in the position shown at *a* in Figure 3, where it is filled. While this filling is taking place the other basket, which is now under the pressure means, is having its contents subjected to the action of the pressure means, so that the filling of one basket and the compressing of the material in the other can take place at the same time.

It will be understood that minor changes may be made in the details of construction without departing from my invention.

I claim:

1. A press comprising a support, a pressure means on the support, the base of the support being recessed and having an annular groove around the mouth of the recess, the base having passages from the groove to the upper part of the recess, a cover on the recess, and a screen mounted in the recess below the passages.

2. A press comprising a support, a pressure means on the support, the base of the support being recessed and having an annular groove around the mouth of the recess, the base having passages from the groove to the upper part of the recess, a cover on the recess, a ring with legs thereon to rest on the bottom of the recess with the ring below the passages, and a screen on the ring.

3. A press comprising a support including a base and a standard, a pressure means on the support, a swinging bracket on the standard, and a basket supported by the bracket, the basket having its top and bottom open, whereby the basket can be swung clear of the base.
4. A press comprising a support including a base and a standard, a pressure means on the support, a swinging bracket on the standard, a basket supported by the bracket, the basket having its top and bottom open, whereby the basket can be swung clear of the base, and means for detachably securing the basket on the bracket.
5. A press comprising a support including a base and a standard, a pressure means on the support, a swinging bracket on the standard, a basket supported by the bracket, the basket having its top and bottom open, whereby the basket can be swung clear of the base, and means for locking the bracket on the standard when the basket is aligned with the pressure means.
6. A press comprising a support including a base and a standard, a bracket swinging on the standard, baskets attachable to the bracket and disposed so as to swing with their bottoms slightly above the level of the base, a pressure means on the standard and above the base, and a shelf of curved form at the level of the base and adapted to support the contents of a basket swung toward the base, said shelf being short enough to permit enough space whereby a basket swung beyond the base can have its contents dropped, the parts being disposed so that the other basket is then in position under the pressure means.
7. A press comprising a support including a base and a standard, a bracket swinging on the standard, baskets attachable to the bracket and disposed so as to swing with their bottoms slightly above the level of the base, a pressure means on the standard and above the base, and a shelf of curved form at the level of the base and adapted to support the contents of a basket swung toward the base, said shelf being short enough to permit enough space whereby a basket swung beyond the base can have its contents dropped, the parts being disposed so that the other basket is then in position under the pressure means.
8. A press comprising a support including a base and a standard, a bracket swinging on the standard, baskets attachable to the bracket and disposed so as to swing with their bottoms slightly above the level of the base, a pressure means on the standard and above the base, a shelf of curved form at the level of the base and adapted to support the contents of the basket swung toward the base, said shelf being short enough to permit enough space whereby a basket swung beyond the base can have its contents dropped, the parts being disposed so that the other basket is then in position under the pressure means, and a latch for stopping the bracket whenever the baskets are in the above described position.

In testimony that I claim the foregoing, I have hereto set my hand, this 10th day of January, 1921.

L. PEROTTI.
